UNITED STATES PATENT OFFICE.

ALADAR HOLLANDER, OF BERKELEY, CALIFORNIA, ASSIGNOR, BY MESNE ASSIGNMENTS, TO BYRON JACKSON PUMP CO., A CORPORATION OF DELAWARE.

VARIABLE-HEAD CENTRIFUGAL PUMP.

Application filed April 23, 1928. Serial No. 271,999.

My invention is particularly applicable to centrifugal pumps, although it may also be used for turbine water wheels wherein the pressure or head in which the impeller operates vary over a wide range.

It is also applicable where different speeds of impeller operation are to be employed over considerable periods of time and with the same operating head.

10 My invention has for its object the provision of means for varying the effective diameter, angle and velocity characteristics, to accommodate changes in head from time to time or in exceptional cases changes in speed, or 15 of speed and head.

It is particularly adaptable to submerged pumps of large capacity and is a modification of the invention set forth in my co-pending application, Ser. No. 227,310 filed October 19, 1927.

By referring to the drawing my invention will be made clear.

Fig. 1 is a vertical cross section through a submerged double centrifugal pump employing my invention, with the parts assembled 25 on the left hand side of the figure for operating under a relatively low head, and with the parts removed on the right hand side of the figure as when it is to be operated under a relatively higher head. The figure is taken 30 on the section line 1, 1 of Figs. 2 and 3 respectively.

Fig. 2 is a cross section through the left hand portion of the runner of Fig. 1 with the 35 parts assembled for operating under the lower head.

Fig. 3 is a cross section through the same runner with the portions adapted to operate under the lower head removed, so that the 40 runner is shown suitable for operating under the higher head.

Fig. 4 is a section on the line IV—IV of Fig. 2 showing the manner of fastening the impeller extensions or low head parts.

45 Throughout the figures similar numerals refer to identical parts.

The main operating shaft adapted to be driven by any conventional means is indicated by the numeral 1.

50 A volute casing into which the water is discharged by the impellers is shown at 2.

Suction inlets are shown at 3, 3 and at 4, 4.

An impeller as indicated at 5, fitted to the

shaft 1 and impeller vanes fixed with the impeller casting 5 are shown at 6, 6.

The impeller is formed with the center disc 7, and with sides at 8, 9 respectively, effecting closure through a running joint in a conventional manner with the casing 2.

Referring particularly to the left hand of Fig. 1 and to Fig. 2 removable pieces 10, 10 are provided which are in effect extensions to the vanes 6, 6 when they are bolted between the disc 7 and sides 8 and 9 and these are held in place by the through bolts 11 (see also Fig. 4).

When these vane extensions 10 are in the position at the left of Fig. 1 the impeller is adapted to operate at a lower head.

It will be noted that under the lower head its peripheral velocity may be maintained the same as the peripheral velocity of the vanes 6 on the right hand side of the figure when the latter is operating under the higher head.

In other words the discharge from the vane extensions 10 under the lower head will be maintained the same as the discharge velocity from the vane 6 under the higher head.

The pump is particularly adapted to large sizes and the manhole 12 in the casing 2 is provided to give access within the casing so that the extension members 10, 10 may be readily removed during seasonal variations in the head to be pumped.

Thus, where the pump is employed on a river having a considerable rise and fall, when the river is low the head to be pumped to an adjacent irrigation ditch would be higher than during seasons of high water.

At such low water season therefore the extensions 10 are employed bolted in place as shown to the left of Fig. 1 and in Fig. 2; whereas during the seasons of high water, when not such a great head is to be raised, the extensions are removed as shown to the left of Fig. 1 and in Fig. 3.

I claim:

1. In a centrifugal pump, a volute casing, an impeller mounted to rotate in said casing and having fixed vanes and a pair of disc sides extending to a greater diameter than said vanes, a plurality of removable members adapted to be detachably fixed between said disc sides and forming extensions to said vanes.
2. In a centrifugal pump, a volute casing,

- an impeller mounted to rotate in said casing and having fixed vanes and a pair of disc sides extending to a greater diameter than said vanes, a plurality of removable members 5 adapted to be detachably fixed between said disc sides and forming extensions to said vanes to substantially the periphery of said sides.
3. In a centrifugal pump, a volute casing, 10 a double impeller having a central diaphragm and a disc side spaced from and on each side of said diaphragm, a plurality of vanes symmetrically positioned between each side and said diaphragm and within a diameter substantially less than the diameter of 15 said sides, a plurality of members adapted to be detachably fixed between each of said sides and said diaphragm and forming extensions to the said vanes.
4. A pump impeller comprising a hub and 20 fixed vanes and a pair of disc sides extending to a greater diameter than said vanes, a plurality of removable members adapted to be detachably fixed between said disc sides and forming extensions to said vanes. 25
5. In a centrifugal pump, a rotor comprising a shaft on which is mounted an impeller, 30 said impeller having fixed vanes and a pair of disc sides extending to a greater diameter than said vanes, a plurality of removable members adapted to be detachably fixed between said disc sides and forming extensions to said vanes.

ALADAR HOLLANDER.
